UNITED STATES PATENT OFFICE.

JOSEPH L. DICKINSON, OF DUBUQUE, IOWA.

SHINGLE-SAWING MACHINE.

SPECIFICATION forming part of Letters Patent No. 450,995, dated April 21, 1891.

Application filed March 9, 1889. Serial No. 302,643. (No model.)

To all whom it may concern:

Be it known that I, JOSEPH L. DICKINSON, a citizen of the United States, residing at Dubuque, in the county of Dubuque and State of Iowa, have invented certain new and useful Improvements in Shingle-Sawing Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention pertains to certain new and useful improvements of machines for sawing shingles, having for its object the production of means whereby a block of wood is fully utilized and the waste material is reduced to a minimum.

The invention comprises an auxiliary carriage capable of being connected to and operated with the main carriage and means for holding a reduced block or "spalt" thereon and presenting the same to the action of the saw; and it also comprises the detail construction, combination, and arrangement of parts, substantially as hereinafter fully set forth, and particularly pointed out in the claims.

In the accompanying drawings, Figure 1 is a view in perspective of my improved shingle-sawing machine, a reduced block or spalt being shown at S. Fig. 2 is a similar but enlarged view of a portion thereof, showing the auxiliary carriage. Fig. 3 is a transverse sectional view on the line $x-x$, Fig. 2. Fig. 4 is a view of the presser-block. Fig. 5 is a perspective view showing the under side of the auxiliary carriage and tilting table.

Referring to the drawings, A designates the frame of the machine, and a the horizontally-disposed circular saw, which is mounted and operated in a manner similar to those now in use.

B is the sliding carriage of ordinary construction, and it is provided with end rods b b, secured so as to slide on rods b' or in grooves of the frame. This carriage has dogs b² b³ for holding the block of wood to be sawed, said bar resting upon the parallel bars C C, composing tilting table C'. This tilting table

is operated by cams B' on a rod or shaft B². (See Fig. 2.) The distance between the top of these bars or tilting table and the saw-gages is the thickness of the shingle. The dogs b² b³ have their ends, which are preferably flattened, secured in slots b⁴ of rods b, so that they can be secured close together or farther apart. The dog b³ is capable of being moved by ordinary links or arms b⁵, secured to a shaft b⁶, having a lever-handle b⁷.

D is an auxiliary carriage, which slides at its ends in grooved guides d, rigidly secured to the frame T adjacent to the side bars of tilting table C'. This carriage provides stops or supports to force the reduced block or spalt to the saw when required—that is, after the block has been sawed to the full extent possible by use of the main carriage and dogs. The auxiliary carriage D is capable of being connected at will to the main carriage B by a pivoted yoke d'. A flat spring d², attached to the under side of carriage D, bears against the lower reduced end of this yoke, which end is extended through a slot in the carriage D, whereby said yoke can be held in engagement with one of the end rods b of carriage B.

E is a stop or support held in place against one end of carriage D by flat springs e, attached at their inner ends to the under side of said carriage, their outer ends being connected to said stop or support. These springs permit the stop or support to have a limited downward movement when the shingle-blocks of heavy wood are thrown thereon. The reduced block or spalt rests against the stop or support, and in the movement of the carriages it is thereby forced against the saw, the spalt being held firmly on the side bars or ways of tilting table C by a presser-block g. An additional stop or support e' is disposed at one side of the carriage D, to which it is secured by a yielding bar e², so that the upper face thereof will be on a line with that of stop or support E. This stop or support e' serves the same purpose as the other stop or support, and also as an additional bearing to prevent the spalt from swinging out of place. It will be understood that these stops or supports are intended for use when the reduced block or spalt is too thin to be held by the ordinary dogs.

F is a guide-bar having an inner projecting rib f, which forms a support for the butt of the shingle when passing beneath the saw, the inner end of said bar being extended under the saw, so as to serve as a support and guide therefor.

To the right-hand or movable dog b² is pivoted a flexible spring-arm G, to the outer end of which is attached a presser-block g, of rubber or serrated metal or other suitable material. This presser-block serves to hold the spalt as it passes to the saw and holds the "sbim" (which is the thin remnant left after the spalt is sawed, being too thin for another shingle or susceptible of being held by the dogs) on the saw and removes it when the carriage is drawn back. The presser-block g, when not in use, can be thrown back out of the way by reason of its spring-arm being pivoted to the back of the dog b² or to the carriage, as seen in Fig. 4.

In practice the block from which the shingles are to be made is placed on the side bars C of the tilting table C' and held by the dogs in the usual manner during the sawing operation. When, however, the block is so far reduced that a firm hold by the dogs cannot be had, it is placed against the stops or supports E e', with the butt-end resting on the rib of and against the guide-bar F, and the presser-block is lowered down to the spalt. When thus secured, the auxiliary carriage is connected to the main carriage by the yoke and is carried forward with said main carriage and the spalt presented to the action of the saw, and the shingle is cut and dropped from the under side thereof. The spalt is then drawn back with the carriage and is again presented until too thin or unsuitable.

It will be seen that by means of my invention a block of wood can be entirely used or consumed in the sawing of shingles, and thus all the wood is utilized and waste thereof is avoided. The parts by which this is accomplished are extremely simple and do not in the least interfere with, but rather promote, the rapid use of the machine.

I claim as my invention—

50 1. As an improvement in shingle-sawing machines, the auxiliary carriage herein described carrying spring-secured or yielding stops or supports for holding a reduced block or spalt for action of the saw, as set forth.

55 2. As an improvement in shingle-sawing machines, the combination, with the main

sliding carriage, of the auxiliary carriage herein described having a detachable connection with said main carriage and provided with yielding stops or supports and a presser-block 60 for holding a reduced block or spalt for action of the saw, as set forth.

3. As an improvement in shingle-sawing machines, the combination, with the main sliding carriage, of the auxiliary carriage herein described, the stationary grooved guideways in which said carriage moves, and the yoke pivotally secured to said auxiliary carriage and designed to engage said main carriage, substantially as set forth. 70

4. In a shingle-sawing machine, the combination, with the main sliding carriage and the auxiliary carriage, of the shingle stops or supports at the longitudinal edge and side of said auxiliary carriage and having flexible connections therewith, substantially as set forth. 75

5. In a shingle-sawing machine, the combination, with the main sliding carriage and the auxiliary carriage, of the shingle stop or support E, the springs secured thereto and to said carriage, the stop e', and the yielding bar connected thereto and to said auxiliary carriage, substantially as set forth. 80

6. In a shingle-sawing machine, the combination, with the main sliding carriage having 85 end rods, of the auxiliary carriage, the pivoted yoke secured thereto so as to engage one of said end rods, and the spring secured to said auxiliary carriage holding said yoke in place, substantially as set forth. 90

7. In a shingle-sawing machine, the combination, with the machine-frame, the horizontally-disposed saw, and the auxiliary carriage having the shingle stops or supports, of the guide-bar F, secured to said frame and provided with a projecting rib forming a guide and support for the end of the shingle and having its forward end extended beneath said saw, substantially as and for the purpose set forth. 95

8. In a shingle-sawing machine, the combination, with the auxiliary carriage, of the shingle-stops E e', connected to said carriage, and the spring-held presser-block, constructed and arranged substantially as set forth. 105

In testimony whereof I affix my signature in presence of two witnesses.

JOSEPH L. DICKINSON.
